UNITED STATES PATENT OFFICE

GEORGES ROUILLER AND JEAN MARION, OF PARIS, FRANCE
CINEMATOGRAPHIC PROJECTING APPARATUS

Application filed June 13, 1928, Serial No. 284,999, and in France July 5, 1927.

Our invention relates to a cinematographic projecting apparatus in which the various parts are improved in such a manner that it presents simultaneously the following advantages:

- 5 (a) An intermittent and noiseless feed;
- (b) The least possible obturation owing to a variable angular movement of the closing device;
- 10 (c) Ventilation of the lamp and of the condenser through the closing device itself;
- (d) Framing of the picture without modifying the synchronization of the obturating device with the driving mechanism;
- 15 (e) An optical system giving the greatest possible output.

Lastly, the various parts of the apparatus are positioned in such a manner as to facilitate its upkeep to render the guiding of the film easier and to reduce the space taken up.

The annexed drawings show by the way of example a mode of execution of an apparatus according to our invention.

Fig. 1 is an outside view of the apparatus (operating side) the wall of the fan being omitted to show the connection of the latter with the driving shaft.

Fig. 1^a is a continuation of Fig. 1 reading from the left hand extremity thereof.

25 Fig. 2 is a part sectional view on line 2—2—2 of Figures 1 and 1^a.

Fig. 3 is a back view of the fan.

Fig. 4 is a diagram showing the movement of the obturator-fan device.

35 Fig. 5 shows a modification of the fan.

As will be seen in the drawings the shaft 3 rotates in a bearing 2 in frame 1 and is actuated by a grooved pulley 4 connected to the driving motor. A gear 5 which rotates the gears 6 and 7 in a 1/1 ratio is secured upon the shaft 3. The gear 6 is connected with a plate 8 provided with a finger 8¹ their driving shaft rotating in a boss of the cover 9 of a casing 10. Said plate 8 drives a Maltese cross 11 upon the shaft of which is secured a sprocket 12 designed to intermittently draw the film forward. The casing 10 carries also a boss 10¹ extending axially from the shaft 3 in which is frictionally mounted

45 an eccentric sleeve 13 which allows of regu-

lating the distance between the plate 8 and the Maltese cross 11 by simply rotating it in the bore of said boss 10¹. The arrangement of the boss of the casing 10 provides for the rotation of the latter in a bore of frame 1 and consequently for the adjustment of the delivery device 12 the movement of which frames or alters the position of the picture relatively to the window of the projecting apparatus. The casing 10 when rotatably adjusted, moves the gear 6, concentrically to the driving wheel 5. As its angular position changes it causes also the angular position of the plate 8 to change relatively to the Maltese cross 11. 14 are friction discs which come into action when the casing rotates. 15 is a locking nut.

55 The framing is produced by the rotation of the casing 10 by means of a lever 16 to which said casing is connected by means of a pin, said lever being pivoted at 18 (Fig. 1^a) to a connecting rod 19 provided with a transverse groove 19¹ and pivoted on the other part at 20 to a lever 21 made in one with a pin 22 which carries a hand lever 23.

70 In the example shown in Fig. 1, the casing 10 is in its upper position. When the handle 23 is moved to the right connecting rod 19 is raised and the box 10 together with the sprocket 12 is lowered. The connecting rod draws along by means of a slide 19¹ a stud 24 fixed on a lever 25 pivoted at 26 with a short lever 27 carrying a stud 28 designed to shift by means of a sleeve 29 a sliding spiral pinion 30 in such a manner that the

75 synchronism between the obturator and the film driving mechanism is not modified by the change in the angular position of plate 8 relatively to the Maltese cross 11, the pinion 30 coming in the driving mechanism as will be seen. Said pinion whose teeth are set at 45° is rotated by a spiral toothed wheel 31 actuated by spiral pinion 32 carried together with the pinion 7 upon a shaft 33 secured upon a boss of the bearing 2. The pinion 30 is mounted upon the shaft 34 in such a manner as to both slide upon it and rotate it. Said shaft 34 is mounted in bearings 35 and 36, provided in two bosses of the frame 1, and it carries upon its end a lever 37 which drives, on the

one part, the connecting rod 38 by means of a crank pin 39 and, on the other part, the obturating device 40 by means of an axle 41 (Figs. 1 and 1^a). Thus when said shaft 34 5 accomplishes a rotation of 90° corresponding to the drawings away of the picture by the delivery device 12, the obturator 40 effects a shorter movement of 60° for example, as will be seen in Fig. 4 and then during the 10 time when the picture remains exposed, the obturator rotates first at an accelerated and afterwards at a slower speed.

The obturating device is loosely mounted upon a pivot 42 it is constituted by three equidistant vanes placed at 60° in the present case thus giving the smallest obturation possible and consequently the maximum of illumination on the screen. The blades are provided with fan blades 40 which are normal to their 20 plane but do not extend to their periphery in order to cover over the obturating device as much as possible without giving an exaggerated dimension to the wings which as they rotate in an helical receptacle 40°, drive 25 fresh air through the tube 43 in the lamp 44 and at the same time between the glasses of the condenser 45.

Fig. 5 shows a modified form of the obturating device. In the case of lamps requiring 30 a strong ventilation the speed of said device may be three times greater and it then comprises a single obturating blade of 180° but also six fan blades.

The system which gives a varying angular 35 speed still obtains and in that case drives a pinion that in its turn drives another pinion rotating three times quicker upon which the obturating device is mounted.

The lamp 46 placed at the back of the obturating device which divides it from the picture, is provided with a ball and socket joint adjustable by means of a knob 47. 48 is the mirror. The light rays fall on the lenses 45 and then converge and cross each 45 other in the tube 49. They are taken up by the lens 50 which may be adjusted in such a manner as to cause the beam of light to converge at the focus of the lens 51, the frame of which slides upon a rod 52. The adjustment 50 is completed by turning a knob 53 which drives the lens carrier by the intermediary of a rack and pinion. The boss allowing the sliding of the frame constitutes a bearing for the stem of the knob 53.

It is well known that in the case of very 55 powerful lamps the diameter is such that it requires condensers having also a large diameter which are too large to illuminate the picture. In the present system, the rays coming from such a condenser cross in order to fall on the lens 50 having a diameter which is equal to the diagonal of the picture put in juxtaposition. At the exit the whole 60 beam of light is gathered in the lens this not

being always possible in ordinary apparatus with large condensers.

The path of the film 54 is as follows:

As it comes from the unrolling device the film passes upon the guiding roller 55 and upon the roller 56 it then engages the delivery device 57 which it surrounds upon a quarter of its circumference owing to the engagement of a roller 58 provided with cheeks with an abutment of the delivery device 57 thus leaving a free space between the bearing surface of the roller and that of the sprocket. This free space allows the passage of the parts of the film where two ends are gummed together without exerting a pressure capable of causing the film to come out of its path. The roller 58 carried by a lever 59 pivoted on the axle 60 of the roller 56 is always kept in engagement with the delivery device 57 by means of a spring carried upon the axle 60. The arrangement is the same as that shown for the lower delivery device.

The upper delivery device 57 is carried by an axle 62 driven by the wheel 64 which is actuated by the pinion 30. The film then passes as it forms a flexible loop in a passage 65 being pressed upon by the tongues 66 acted upon by the pressure of springs 67 secured to the door 68 which is closed by a bolt 69. A pressure roller 70 elastically mounted owing to buttonholes formed in its frame and to a spring 71 secured by a screw 72 upon an axle 73 is supported by two bosses provided on the door 68. Coming out of the passage the film moves along between the delivery device 12 and the pressure roller 70 and after forming a flexible loop it engages the lower delivery device 57 in the manner already described concerning the upper delivery device 57. The axle 75 of the lower delivery device rotates in rings 63 fitted in bosses provided in the frame. The spring 61¹ presses the roller 58¹ against said delivery device in the manner already indicated. The film is then wound a pulley (shown in Fig. 110 2) 74 being provided for this object at the end of a shaft 75 which is split at its other end to allow of its being eventually actuated by means of a handle.

It will be understood that we do not limit ourselves to the particular arrangement hereinbefore specifically described inasmuch as many modifications may be made in the construction and arrangement of the apparatus without departing from the principle of our invention.

What we claim and desire to secure by Letters Patent of the United States is:

1. In a cinematograph projection apparatus, an obturator having equidistant vanes and a central axis of rotation, fan blades on the vanes, a lantern, a casing enclosing the obturator and discharging into the lantern, a pin on the obturator eccentric to said axis, a driving shaft for the obturator, a crank on

the shaft, a link connecting the crank and pin, means to feed a film, means to frame a picture on the film, said film feeding means and framing means connected with the shaft to maintain the synchronism of the film feeding means and obturator during framing.

2. In a cinematograph projection apparatus, an obturator having equidistant vanes and a central axis of rotation, fan blades on the vanes, a casing for the obturator, a lantern, means to connect the lantern and casing, a pin on the obturator excentric to the axis, a driving shaft, a crank thereon, a link connecting the crank and pin, a power driven main pinion, a second pinion driven thereby, a casing, a film delivery mechanism in said casing and driven from said second pinion, manual means to rotatively adjust said casing and simultaneously adjust the second pinion peripherally of the first pinion, a spiral pinion adjustable on said shaft by said manual means, a lower delivery device drivable from said main pinion and meshing with said spiral pinion to drive the obturator shaft, an upper delivery device driven by said spiral pinion, said lower delivery device arranged to be manually driven when the apparatus is not driven from the power pinion.

30 In testimony that we claim the foregoing as our invention, we have signed our names.

GEORGES ROUILLER.
JEAN MARION.
